UNITED STATES PATENT OFFICE.

JOHN H. SHEETS, OF NEW YORK, N. Y.

DESIGN FOR A NECKTIE-RETAINER.

SPECIFICATION forming part of Design No. 28,977, dated July 5, 1898.

Application filed May 19, 1898. Serial No. 681,168. Term of patent 31 years.

To all whom it may concern:

Be it known that I, JOHN H. SHEETS, a citizen of the United States, residing at New York, (borough of Manhattan,) in the county 5 of New York and State of New York, have invented and produced a new and original Design for a Necktie-Retainer, of which the following is a specification.

My invention relates to a new and original 10 design for necktie-retainers, all of which will be fully and clearly hereinafter described and claimed, reference being had to the accompanying drawings, in which—

Figure 1 represents a front view of my design. Fig. 2 represents a rear view. Fig. 3 15 represents a side elevation.

The leading and essential features of my design reside in the general outline and configuration of the article.

20 The retainer, as illustrated in the drawings, comprises the necktie-retaining loop or hook

portion 1 and the collar-retaining loop or hook portions 2 and 3. The lower ends 4 and 5 of the portions 2 and 3 are bent upon themselves to form hooks to catch under the collar, substantially as shown in Figs. 1, 2, and 3. The portions 2 and 3 are also provided with inwardly-curving portions 6, forming humps. 25

My retainer from a front or rear view resembles in appearance an inverted-Y formation, the difference residing in the curved or rounding formation of the two arms or branches, (see Figs. 1 and 2,) and from a side view it presents substantially the form of an elongated S. (See Fig. 3.) 30

I claim as my invention—

The design for a necktie-retainer substantially as herein shown and described.

JOHN H. SHEETS.
